UNITED STATES PATENT OFFICE

148,671

DESIGN FOR A WATCH BAND

Paul E. Babin, New Orleans, La.

Application June 17, 1946, Serial No. 130,807

Term of patent 3½ years

(Cl. D45—4)

To all whom it may concern:

Be it known that I, Paul E. Babin, a citizen of the United States, residing at New Orleans, in the county of Orleans and State of Louisiana, have invented a new, original, and ornamental Design for Watch Band, of which the following is a specification, reference being had to the accompanying drawing, forming part thereof.

Figure 1 is a perspective view of a watch band, showing my new design;

Figure 2 is an elevational view;

Figure 3 is a top plan view;

Figure 4 is a fragmentary longitudinal sectional view through a part of the watch band, between and parallel to its edges.

I claim:

The ornamental design for a watch band, as shown and described.

PAUL E. BABIN.
